UNITED STATES PATENT OFFICE

CHRISTIAN KRÄMER, OF BERLIN-PANKOW, GERMANY, ASSIGNOR TO GENERAL ELECTRIC COMPANY, A CORPORATION OF NEW YORK

MERCURY ARC RECTIFIER

Application filed October 4, 1929, Serial No. 397,398, and in Germany January 30, 1929.

My invention relates to rectifiers, and has for its principal object the provision of an improved anode structure whereby the current carrying capacity of the rectifier is 5 greatly increased.

The power carrying capacity of rectifiers such as the mercury arc is limited by arc-backs occurring when the individual anode current exceeds a certain value. This current differs for each operating voltage and vapor pressure but there is a definite valve for each set of conditions above which it is impossible to load a rectifier. In order to increase the total power carrying capacity of a rectifier, it is customary to increase the number of anodes. This increase in the number of anodes is objectionable because of the accompanying increase in the number of seals, increase in the size of the tank, and 20 complications in the connections.

In accordance with my invention these objections are overcome in that, instead of the plurality of parallel anodes, I provide an anode structure comprising a single anode stem arranged to be sealed into the tank and to support a plurality of anodes, a shield being arranged to surround the structure and provide an individual arc path to each of said anodes.

My invention will be better understood from the following description when considered in connection with the accompanying drawing and its scope will be pointed out in the appended claims.

Referring to the drawing, Fig. 1 illustrates a section of a rectifier provided with anode structures built in accordance with my invention; Figs. 2 and 3 illustrate other sectional views of the anode structure illustrated in Fig. 1; Fig. 4 is a diagrammatic view of the rectifier illustrating the paths of arcs traveling between the cathode and the anode circuit; and Figs. 5, 6, 7 and 8 illustrate modifications of the invention.

Fig. 1 illustrates a partial cross-section of a rectifier 10 provided with anode structures 11 surrounded by shields 12. The structure 11 is supported by, and insulated from the tank 10, by an insulator 13 and comprises a stem 14 provided with a long flattened por-

tion 14' upon which the arc receiving members or anodes 15 are mounted. The anodes 15 are arranged in vertical order upon the stem 14'. They may be made of iron, graphite or any other suitable material which is 55 not attacked by mercury vapor. The shield 12 surrounds the structure and may be provided on its outer side with a slot. Preferably, however, the shield 12 is provided with a plurality of openings provided with inserts 60 16 which form short lengths of tubing attached to the shield and are arranged to extend into close proximity to the ends of anodes 15, and register with the active surfaces of the anodes, thereby forming individual 65 effective arc paths to each anode.

Fig. 2 is a cross-section view through the shield 12, insulator 13 and anode 15, illustrating the front elevation of stem 14'. Fig. 3 is a horizontal cross-section view through shield 12 illustrating the arrangement of an insert 16 in relation to an anode 15. 70

Fig. 4 is a diagrammatic view of a rectifier 10 illustrating by lines 17 the paths of arcs traveling between the cathode 18 and the 75 anodes 15.

Figs. 5, 6, 7 and 8 illustrate modifications of the anode structure and methods for obtaining equal division of current between the anode. Fig. 5 is a horizontal cross-section view of shield 12 provided with inserts 19 arranged to extend around anode 15. A collar 20 of magnetic material, such as iron for example, is mounted upon insert 19 in order to act as an arc choke. Since the choking 80 effect is proportional to the current flow, a substantially equal division of the current between the different anodes 15 is obtained.

Fig. 6 illustrates a modification of the invention similar to Fig. 5 in which an insert 90 21, made of insulating material, is used and an insulating shield 22 is provided between the stem 14 and the insert 21. In this modification the insert 21 is lengthened to extend 95 up to the insulating shield 22 and is allowed to project beyond the shield 12. The collar 20 in this modification effects the equal division of the current in the same manner as the construction illustrated in Fig. 5. A lengthening of the insert and the provision of the 100

insulating shield 22 which may be of mica, ceramic or any other material, affords protection of the stem 14' against the heat of the arc.

5. Figs. 7 and 8 illustrate a modification of the stem 14. Figs. 7 and 8 are respectively a front elevation and a side elevation of this modification. In Fig. 8 the stem and attached anodes 15 are shown in operating position in a rectifier 10, the anode structure being surrounded by the shield 12 provided with the lengths of tubing 16 having openings registering with the active surfaces of the separate anodes. In order to obtain an 10 equal division of current between the anodes 15, the stem 14 is divided into laminations 23 having insulation between them. Each member 15 is attached to one of the laminations 22 and in such manner that the anodes 15 farthest away from the cathode is attached 15 to a lamination having the least resistance whereas the member 15 closest to the cathode is attached to the lamination having the highest resistance so that the total voltage 20 drop between the anode terminal and the cathode will be substantially the same for 25 all anodes 15.

What I claim as new and desire to secure by Letters Patent of the United States is:

30 1. An anode structure for a rectifier including a stem, a plurality of anodes mounted one below the other upon said stem and projecting laterally therefrom, and a shield surrounding said stem and anodes and provided with openings registering with each 35 of said anodes.

2. An anode structure for a vapor discharge device, including a stem, said stem having a resistance which increases toward 40 the lower part thereof, a plurality of anodes mounted one below the other upon said stem and projecting laterally therefrom, and a shield surrounding said stem and anodes and provided with a plurality of openings registering with said anodes respectively.

3. An anode structure for a vapor discharge device including a stem, a plurality of anodes mounted upon said stem, and a shield surrounding said stem and anodes 50 and provided with a plurality of openings which register with said anodes respectively, and tubes mounted in said openings and extending from said shield toward said anodes.

55 4. An anode structure for a vapor discharge device including a stem, a plurality of anodes mounted upon said stem, and a shield surrounding said stem and anodes and provided with a plurality of openings registering with said anodes respectively, tubes mounted in said openings and arranged to surround said anodes, and a plurality of shields of insulating material disposed respectively between said stem and the ends 60 of said tubes.

5. An anode structure for a vapor discharge device including a stem, a plurality of anodes mounted upon said stem, and a shield surrounding said stem and anodes and provided with a plurality of openings registering with said anodes respectively, and insulating tubes mounted in said openings and surrounding said anodes. 70

6. An anode structure for a vapor discharge device including a stem, a plurality of anodes mounted upon said stem, a shield surrounding said stem and anodes and provided with a plurality of openings registering with said anodes respectively, insulating tubes mounted in said openings and surrounding said anodes, and rings of magnetic material surrounding said tubes. 75

80 7. An anode structure for a vapor discharge device provided with a stem including laminations having a predetermined resistance to current flow, an anode attached to each of said laminations and a shield surrounding said stem and anodes and provided with openings registering with said anodes respectively. 85

8. An anode structure for an electric discharge device including a cathode, said structure being provided with a laminated stem, the laminations of said stem being insulated from one another and having a predetermined resistance to current flow, and anodes mounted upon said laminations, the anode nearest to the cathode being mounted upon the lamination having the greatest resistance. 90

In witness whereof, I have hereunto set 100 my hand this 18 day of September, 1929.

CHRISTIAN KRÄMER.
